Primary Examiner—Ralf Seifert**[57] CLAIM**

The ornamental design for an identification bracelet for a baby bottle, as shown and described.

DESCRIPTION

FIG. 1 is a perspective view of an identification bracelet for a baby bottle showing my new design;

FIG. 2 Is a top plain view of the bracelet as shown;

FIG. 3 Is a right hand side elevation of the bracelet;

FIG. 4 Is a bottom plain view of the bracelet;

FIG. 5 Is a left hand side elevation of the bracelet;

FIG. 6 Is a right hand end elevation of the bracelet; and,

FIG. 7 Is a left hand end elevation of the bracelet.

The broken line showing of a bottle in FIG. 1 and indicia in FIGS. 1 and 2 are for illustrative purposes only and forms no part of the claimed design.
